UNITED STATES PATENT OFFICE.

GEORGE ALFRED HOUSEMAN, OF EL PASO, TEXAS.

TATTING-SHUTTLE.

1,306,692.

Specification of Letters Patent. Patented June 17, 1919.

Application filed February 8, 1918. Serial No. 216,081.

To all whom it may concern:

Be it known that I, GEORGE ALFRED HOUSEMAN, a citizen of the United States, residing in the city of El Paso, county of 5 El Paso, State of Texas, have invented new and useful Improvements in Tatting-Shuttles, of which the following is a specification, reference being had to the accompanying drawing.

10 The present invention relates to new and useful improvements in shuttles and more particularly to that class designed especially for use in making tatting and the like.

15 The primary object of the invention is the provision in a shuttle of means for winding the thread by crank and gears, and holding the thread by spring tension to prevent fast unwinding while in use.

20 A further object of the invention is the provision of a shuttle which will be comparatively simple and inexpensive to manufacture, reliable and efficient in use, and readily operated.

25 With the above and other objects in view, the present invention resides in the novel features of construction, formations, combinations and arrangements of parts to be hereinafter more fully described, claimed, and illustrated in the accompanying drawing forming a part of the present application, and in which;

Figure 1 is a side elevation thereof;

Fig. 2 is a longitudinal sectional view thereof;

35 Fig. 3 is a plan view thereof; and

Fig. 4 is an enlarged detail sectional view taken through the central portion of the device.

40 Referring now to the accompanying drawing by corresponding characters of reference throughout the several views, the numeral 5 designates in general my improved shuttle which consists of a pair of side members 6 curved inwardly toward each other at their 45 ends as at 7; and one of said ends being elongated to form a pick 7' for use in handling yarn.

A drum is shown at 8 and is journaled on a stub shaft 9 which connects the opposite 50 side members 6 intermediate their ends and holds them in their normal position.

The opposite ends of the drum 8 are pro-

vided with suitable flanges 10, one of which is provided with gear teeth 11 around its periphery which mesh with a pinion 12 secured to one of the side members in spaced relation to the shaft 9.

55 The gear 12 is provided with an angular recess 13 therein which removably receives one end of an operating crank shown at 14.

60 The gear 12 is provided with a sleeve 15 which extends through an opening 16 formed in the said side member while its outer end is riveted as at 17 to prevent the displacement of the gear.

65 If desired, a suitable gasket shown at 18 may be disposed between the riveted portion 17 of the gear and the adjacent portion of the side member 6.

70 In order to prevent any retrograde movement of the gears, a spring pawl 19 is provided. This pawl 19 is secured as at 20 to one of the side members and has its free end disposed in engagement with the teeth of the gear 12. It is positioned in such manner that the gear can rotate in either direction.

75 In use, the thread is wound upon the drum 8 by means of the crank 14, after which the crank may or may not be removed 80 as desired and the thread can be taken from the drum and used as desired, the pawl 19 holding the drum under tension so that it will prevent any undesired unwinding of the thread. The pick 7' is of use in untangling knots and otherwise facilitating the handling of the material being worked.

85 From the foregoing description taken in connection with the accompanying drawing, it will be manifest that a tatting shuttle is 90 provided which will fulfil all of the necessary requirements of such a device, and it should be understood in this connection that various minor changes in the specific details of construction can be resorted to within the 95 scope of the appended claim without departing from the spirit or sacrificing any of the advantages of the invention.

Having thus fully described the invention, what I claim to be new and desire to protect by Letters Patent is:

100 A gear mount for tatting shuttles, including a frame, a spool rotatably mounted therein, spur gear teeth cut around one of

the flanges of the spool, a sleeve rotatably mounted in the frame adjacent said gear teeth, a pinion permanently mounted on the inner end of the sleeve and in mesh with 5 said gear teeth of the spool, an angular, central opening formed through said sleeve, a crank rotatably mounted through the oppo-

site side of the frame and having an angular end to detachably engage said angular central opening in said sleeve.

GEORGE ALFRED HOUSEMAN.

Witnesses:

GOWAN JONES,

RUTH WEST.
